UNITED STATES PATENT OFFICE.

JOHN HUME BELL, OF EAST ORANGE, NEW JERSEY, ASSIGNOR, BY MESNE ASSIGNMENTS, TO WESTERN ELECTRIC COMPANY, INCORPORATED, A CORPORATION OF NEW YORK.

LEAK-NULLIFYING MEANS FOR TELEGRAPH SYSTEMS.

1,183,946.

Specification of Letters Patent.

Patented May 23, 1916.

Application filed March 4, 1915. Serial No. 11,937.

To all whom it may concern:

Be it known that I, JOHN H. BELL, a subject of the King of Great Britain, residing at East Orange, in the county of 5 Essex and State of New Jersey, have invented certain new and useful Improvements in Leak-Nullifying Means for Telegraph Systems, of which the following is a full, clear, concise, and exact description.

10 This invention relates to telegraph systems and more particularly to leak-nullifying means for telegraph systems.

The object of this invention is to provide a new and improved means for nullifying or rendering ineffective, with respect to the intermediate stations upon the line, the current leaks due to high resistance grounds upon the line between the terminal stations.

20 In accordance with the features of this invention, there is provided at each end of the line a double-wound relay normally energized over a local circuit to maintain the line closed, but which relay is adapted, 25 upon the operation of the telegraph relay at its associated station, to open the line. The double wound relay has connected with one winding a condenser, the discharge of which causes the deenergization of said double-wound relay to open the line circuit and thus remove the effects of ground at the intermediate stations.

The drawing is a circuit diagram of a system wired in accordance with this invention.

In the drawing A and D designate terminal stations, and B and C intermediate stations connected with a line 5. Located at each of the terminal stations A and D 30 is a key 6, a relay 7 in the main line circuit, a sounder 8 in a local circuit, and a relay 9. The relay 9 has two windings 10 and 11, the winding 10 being normally energized from a local battery 12 through 35 a resistance 13 to ground. The winding 11 of the relay 9 is included in a circuit with a condenser 14 and a resistance 15 adapted to be closed through the front contact 16 of the relay 7. An armature 17 of 40 relay 9 is adapted when said relay is energized, to close a contact 18 to maintain the continuity of the line 5. Batteries 19 and 45 20 of opposite polarity, located at the ter-

55 minal stations, are normally closed to line through the keys 6.

Referring now to the operation of the system, it will be noted that the armature 17 of the local relay 9 is normally held attracted due to current through the winding 10 from the battery 12. Assume that the 60 line is subject to heavy leakage but that station A can communicate with station D. When A opens his key in order to call station C, a current will still be flowing from the battery 20 at D, through the relays at 65 B and C due to the line leakage. The adjustment of relay 7 at station D however, is such as to enable it to respond to the actuation of the key 6 at station A, but the relays at B and C being normally given less 70 skilled attention than at the terminal station D may be out of adjustment with respect to the signals from station A, and consequently not to be actuated. Their armatures may, therefore, be held up due to 75 the current from battery 20 at station D feeding the leakage between B and A, and may not respond to the current impulses sent out from station A. When the opening of the circuit at station A causes the 80 line relay armature at station D to fall back, the condenser 14 discharges through the winding 11 of the local relay. This discharge impulse produces a magnetic flux opposing and preponderating over that set up by the steady current through winding 10, so that momentarily the armature of the local relay falls back, thus opening the line 85 circuit at station D. When this occurs, the armatures of the relays at the intermediate 90 stations which may have been held up due to line leakage, will drop back and thus be in position to respond to signals from the terminal or intermediate stations. The great advantage of this scheme is that it 95 requires, in addition to the usual apparatus at each of the terminal stations, only one relay, the condenser and two resistances, and can be readily added to already existing equipments with but slight changes in the 100 wiring.

What is claimed is:

1. In a telegraph system a line circuit, terminal stations and intermediate stations connected therewith, a source of current at 105 each terminal station normally connected

- with the line, a relay at each terminal station, a contact closed by said relay when energized for maintaining the continuity of said line circuit, a continuously closed energizing circuit for said relay, and a deenergizing circuit for said relay rendered momentarily effective by the opening and closing of a sending key whereby the continuity of said line circuit will be momentarily interrupted.
2. In a telegraph system a line circuit, terminal stations and intermediate stations connected therewith, a source of current at each terminal station normally connected with the line, a double wound relay at each terminal station, a contact closed by said relay when energized to maintain the continuity of the line circuit, a continuously closed energizing circuit through one winding of said relay, a condenser in series with the other winding of said relay, and means for charging and discharging said condenser through said second named winding upon the opening and closing of a telegraph key whereby said relay will be momentarily deenergized to open the line circuit.
3. In a telegraph system a line circuit, terminal stations and intermediate stations connected therewith, a source of current at each terminal station normally connected with the line, a double wound relay at each terminal station, a contact closed by said relay when energized to maintain the continuity of the line circuit, a continuously closed energizing circuit through one winding of said relay, and means for charging and discharging said condenser through said second named winding upon the opening and closing of a telegraph key whereby said relay will be momentarily deenergized to open the line circuit.
- In witness whereof, I hereunto subscribe my name this sixteenth day of February A. D. 1915.

JOHN HUME BELL.
